US0D1049371S

(12) **United States Design Patent** (10) **Patent No.:** **US D1,049,371 S**
(45) **Date of Patent:** **** Oct. 29, 2024**

(54) **INFUSION PUMP CASSETTE**

(71) Applicant: **Takeda Pharmaceutical Company Limited**, Osaka (JP)

(72) Inventors: **John Kenneth Hainsworth**, Cambridge (GB); **Matthew John Garwood**, Kedington (GB); **Matthew Ian Murchie**, Cambridge (GB); **Hong Choo Tang**, Cambridge (GB); **Jason Robinson**, Tewksbury, MA (US)

(73) Assignee: **Takeda Pharmaceutical Company Limited**, Osaka (JP)

(**) Term: **15 Years**

(21) Appl. No.: **29/831,175**

(22) Filed: **Mar. 17, 2022**

(51) LOC (14) Cl. **24-02**

(52) U.S. Cl.

USPC **D24/127; D24/111**

(58) **Field of Classification Search**

USPC D24/186, 127-130, 107, 108, 110, 164; D15/9

CPC A61M 3/0279; A61M 39/105; A61M 1/86; A61M 1/0088; A61M 1/0052

(57) **CLAIM**

The ornamental design for an infusion pump cassette, as shown and described.

DESCRIPTION

FIG. 1 is a top, front, left side perspective view of an infusion pump cassette;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom view thereof; and,

FIG. 8 is top, rear, right side perspective view thereof.

The short dash-long dash broken lines illustrate boundaries of the claimed design and form no part of the claimed design. The dash-dash broken lines illustrate portions of the infusion pump cassette that form no part of the claimed design.

1 Claim, 8 Drawing Sheets
